RAZOR HANDLE

Martin Glaberson, 200 Huntington Road, Stratford, Conn.
06497, and George L. Schick, 20 Gwendolyn Drive,
Trumbull, Conn. 06611

Filed Feb. 15, 1973, Ser. No. 332,959

Term of patent 14 years

Int. Cl. D28—03

U.S. Cl. D95—3 A

Fig. 1

Fig. 2

Fig. 3

Fig. 4

Fig. 5

FIG. 1 is a front elevational view of a razor handle showing our new design;

FIG. 2 is a rear elevational view thereof;

FIG. 3 is a side elevational view thereof, the side not shown being a mirror image of that shown in FIG. 3;

FIG. 4 is a top plan view thereof; and

FIG. 5 is a bottom plan view thereof.

We claim:

The ornamental design for a razor handle, as shown and described.
